UNITED STATES PATENT OFFICE

SIDNEY W. WINSLOW, JR., OF BROOKLINE, MASSACHUSETTS, ASSIGNOR TO UNITED SHOE MACHINERY CORPORATION, OF PATERSON, NEW JERSEY, A CORPORATION OF NEW JERSEY

SHOEMAKING

Application filed September 18, 1922, Serial No. 538,973. Renewed December 3, 1929.

This invention relates to the art of making shoes, and particularly concerns methods of and means for securing the outsoles to the insoles and associated uppers.

There have been developed, as is illustrated in an application Serial No. 255,209, filed in the United States Patent Office in the name of Laurence E. Topham on September 21, 1918, automatic machines for stitching the outsoles of welted shoes to the welts. In such apparatus, a shoe operated upon has within it a last, which is engaged by a jack, and to this jack movements are imparted to cause the correct presentation of the outsole and welt to stitching mechanism which effects the attachment. In other types of shoes, as those in which the outsoles are nailed, pegged or McKay-sewed to the insole, the mechanism which inserts the fastenings includes an element, customarily in the form of a horn, which must act within the shoe, and consequently the last must be removed from the shoe during this operation. Heretofore, so far as I am aware, it has been impossible to apply manufacturing methods of the above-indicated character to these shoes, because of inability to properly support the work for the operation. An object of my invention is to provide for holding a shoe independently of a last, so that it may be presented effectively to an operating mechanism and control exercised over the relation between said operating mechanism and the work. To this end, I prefer to grasp the shoe by the outsole, which has been at least temporarily attached to the insole and associated upper, its position having best been gaged with reference to adjacent portions of said upper. While thus held, the interior of the shoe is left entirely free to receive portions of the operating mechanism, and if the work is to travel in the operation upon it, this movement may be controlled accurately, so that the stitches or other fastenings may be inserted along a predetermined path.

It is desirable that the relation of the inserted fastenings to the peripheries of the outsole and insole shall be quite exactly determined, since these fastenings are commonly placed along a previously-formed chan-

nel in the outsole, to be concealed by a turned-down channel-flap, and, to insure the continuity of connection between the two soles, all the fastenings should enter the insole. On the other hand, the fastenings should not be placed so far into the insole from the edge as to leave any considerable portion free to curl under the influence of moisture and heat in wear, rendering the shoe ill-appearing and uncomfortable. A further object of the invention is to effect this correct relation of the fastenings, and for this purpose I apply a positioning member to the shoe-sole, the associated elements being left free for manipulation by the operator, and perform the desired operations under the influence of this member. The positioning member may take the form of a templet, which is definitely related to the shoe-bottom by locating means formed thereon. The templet may be caused to perform a double function by acting in conjunction with pressure against the opposite face of the sole to hold the shoe for the operation upon it.

The use of a positioning member or templet as above indicated, is considered to be an important feature of the present invention, which feature, in its broader aspect, is not limited to the performing of operations upon a shoe from which the last has been removed.

In the accompanying drawings, which illustrate one of the many embodiments which an apparatus for performing my novel method may assume,

Fig. 1 is a partial front elevation of a McKay stitching machine provided with an automatic jack;

Fig. 2 is a side elevation, looking from the left in Fig. 1, with parts broken away;

Fig. 3 is a top plan view of the automatic actuating mechanism for the jack;

Fig. 4 shows in broken side elevation the jack in its work-receiving position;

Fig. 5 is a perspective detail view, with parts broken away, of the releasing mechanism for the jack;

Fig. 6 shows, in perspective, the sole-engaging elements holding a shoe for the operation upon it;

Fig. 7 is a front elevation of a portion of

an apparatus for temporarily attaching the outsole to the shoe-bottom, it especially illustrating the gaging mechanism; and

5 Figs. 8 and 9 show, in perspective, this gaging mechanism in co-operation with the heel and toe-portions, respectively, of a shoe.

10 I have chosen to present my invention in connection with the securing of the outsoles of McKay shoes, though it is to be understood that it may be of utility when applied to different operations upon other portions of shoes of dissimilar types. There appears at A in the drawings a stitching apparatus, which, as far as its general characteristics 15 are concerned, may correspond to those disclosed in United States Patents No. 1,050,568, Scott, January 14, 1913, and No. 1,177,581, Meyer, March 28, 1916. A head 10 is carried by a bracket 12 rising from a base-casing 14. Mounted to move upon the head is actuating mechanism for a needle-bar 16, a cast-off 18 and a feed-point 20, all of which co-operate as usual to form successive stitches through the work and advance said work to 25 receive a series of the stitches. Associated with these elements in the formation of the stitches is a whirl 22 rotatable in the upper extremity of a horn 24, the lower end of which is arranged to turn in a bearing 26 in a bracket 28 projecting from the front of the casing. The whirl is connected by gearing 30 contained in the base of the horn and brackets 28 and 12 to gearing 32 located in the head of the stitcher and thereby to the main driving mechanism. The work is held down upon the supporting horn for the production of stitches by a presser-foot 34 vertically movable in the head upon a spring-actuated bar 36. Mechanism, a portion of 30 which appears at 38, serves to raise the presser-foot at the termination of each stitch-producing cycle to permit the feed of the work, and joined to this mechanism is an arm 40, to which may be applied force 35 to lift the presser-foot at the end of the stitching operation, to free the shoe for removal and allow the application of another shoe. This last connection will later be more particularly referred to.

35 Carried upon the base-casing 14 is a jack or work-support B, which is arranged to grasp a shoe by its exterior for submitting it to the action of the operating mechanism, this leaving the interior entirely free for the entrance and movement of the horn. This jack is shown as consisting of two relatively movable supporting members 42 and 44. The first is preferably formed integrally with a short, hollow standard 46 situated below the bearing of the horn and extending in a substantially vertical direction. The lower portions of the jack members are U-shaped in transverse section, and they are curved from the standard 46 outwardly and upwardly, so that they completely clear the

horn 24 and its mounting, permitting a work-controlling movement of the jack and also rotation of the horn without interference between these two elements. The upper extremity of the member 42 is divided into diverging arms 48, 48, lying substantially horizontal and at their outer ends returning into close proximity to each other. The associated jack member 44 is pivoted at 50 upon the standard 46, first passing upwardly within the associated member, and then somewhat diverging therefrom, it terminating in a generally horizontally extending socket 52, shown as rectangular in cross-section and open at both ends. This socket is adapted to receive and hold firmly a shank 54 formed upon one end of a templet 56 for positioning the work with relation to the stitching mechanism, as by contact with the side of the presser-foot at 58. The templet 56 has locating projections 60, of which two are illustrated (Fig. 6), these extending downwardly from the templet at the heel-seat-end and being spaced from one another along the longitudinal axis. They are arranged to enter correspondingly spaced openings 300 in the heel-seat-portion of the outsole 302 of a shoe 304. Rising from the opposite face of the templet from the projections 60 is a flange 62, somewhat greater in height than the turned-up flap 306 of the sole to be operated upon and corresponding in contour to the groove 308 of the channel 310 in the outsole. When the shank 54 is seated in the socket 52, the templet becomes one of opposite members arranged to grasp the upper and lower faces of an outsole and hold it with the attached elements for operations upon it or upon the associated parts.

40 Mounted upon the jack member 44 and acting with the templet is an opposite pressure member 64. This is shown as arcuate in form, being curved to embrace the counter-portion of the upper 312 of the shoe 304 and to present an upper plane surface to the adjacent face of the outsole. From the pressure member is an outward and downward extension 66 arranged to move in ways 68 in the jack member 44. These ways incline upwardly toward the companion jack member 42, so that as the pressure member is raised, it may be introduced into the crease beneath the outsole. Formed upon the outer face of the portion 66 is a rack 70, with which meshes a gear-segment 72 upon a lever 74 fulcrumed upon the jack member 44 just beneath the socket. The upper portion of this lever consists of a curved arm 76, the extremity of which projects within the rear of the socket, where it is normally held by a spring 78 extending between the arm 44 and the lever beneath its fulcrum.

45 To co-operate with the templet in its grasp upon the sole at the opposite or toe-end of the shoe, the member 42 has, fulcrumed at the

outer junction of its arms 48, a lever 80 arranged to swing vertically. At the inner side of this lever is a cam-depression 82 (Fig. 4), which is formed between an overhanging upper projection 84 and a lower projection 86, preferably somewhat less sharply curved than the associated projection. A spring 88 acts between the jack member and lever to urge the projection 84 of the latter downwardly. When the members 42 and 44 are drawn together to clamp the shoe upon the jack, the forward edge of the outsole is thrust against the depression 82, the approach being indicated in dotted lines in Fig. 4, and rides up the projection 84, thus swinging the lever about its fulcrum and forcing the projection 86 upwardly against the under surface of the sole, which is thereby pressed against the templet. At each side of the sole-holding lever 80 is shown a gage-lever 90, pivoted upon the upper, outer extremity of the corresponding arm 48, said gage-levers being geared at 92 to move together (Fig. 6). These levers have curved arms arranged to contact with the opposite edges of the outsole at each side of the toe, and are pressed toward each other by a spring-actuated plunger 94, which contacts with one of them. In their normal position, these lever-arms are sufficiently close to each other to simultaneously engage the narrowest sole which may be applied to the jack, and when this is carried between them, the uniform force which they exert in opposite directions serves to aid the engagement of the templet-shank with the socket 52 in holding the sole in the correct position to receive the action of the stitching mechanism.

To draw the members 42 and 44 together into their work-holding relation, a tension-spring 96 extends between them. They are releasably maintained in their work-receiving position by a toggle-lever 98, which, when straightened, spaces the members sufficiently to permit the application of a shoe with its templet to the jack, and, when broken, allows the spring 96 to draw the members together, bringing the toe-end of the sole into co-operation with the clamping lever 80. A spring 100 is provided between the outer extremity of one of the toggle-arms and the member 44, which has the effect of bringing the two arms into alignment when the jack members are separated. I prefer to utilize the movement produced by the application of a shoe with its templet to the jack for breaking the toggle. When the lever 74 is turned upon its fulcrum by the contact with its end 76 of the templet-shank 54, a projection 102 from its side engages the hooked end of an actuating member 104 mounted within the jack member 44 and arranged to slide along and oscillate about a pin 106 set in said member and projecting through a slot 108 in the actuating member. The latter is held normally lowered

by a spring 110 connecting it with the member 44. At its lower extremity, it is hooked for contact with a projection 112 upon the extremity of the adjacent arm of the toggle 98. When the lever 74 is turned by the shank 54 striking its end 76, the projection 102 rotates in a contra-clockwise direction (Fig. 4), lifting the slide 104. This, through its opposite hooked end, turns the left-hand arm of the toggle clockwise, breaking this and allowing the spring 96 to draw the members 42 and 44 together. In this movement of the toggle, a cam 114, formed upon the toggle-arm adjacent to the projection 112, contacts with the slide 104 to disengage the lower hook from the projection, thus permitting the spring 110 to lower the slide into position for the succeeding operation of the jack. This is as illustrated in Fig. 1 of the drawings.

The jack, as will later be more fully described, is automatically moved to bring that portion of the sole which is to be secured into co-operation with the stitching mechanism, this movement including rotation of the jack through about 180 degrees, and a reverse rotation to the initial position. During this return of the jack to normal, the member 44 is swung upon the member 42 to release the work, and is locked in this open relation ready for the reception of the next shoe to be operated upon. This is accomplished in the following manner: The standard 46 is connected by a gimbal joint 116 (Fig. 5) to a wheel 118 (Fig. 2) rotatable upon a vertical stud 120 mounted in a frame 122 carried by an arm 124 pivoted within the base-casing 14. United to the top of the stud by a gimbal joint 126, so that it may share in the universal tilting movement of the standard 46, though held against rotation therewith, is a spindle 128, having fixed to its upper extremity within the jack-standard a cam 130. Contacting with this cam is a roll 132 rotatable at the top of a bar 134 pivoted in a recess 136 at the lower end of the jack member 42 adjacent to its pivot 50. The recess and bar are shown as rectangular in section, the bar fitting within the recess to move about its pivot against the force exerted by a spring-actuated plunger 138, yet being held against movement in a lateral direction by contact with the walls of the recess. During the rotation of the jack in the direction of the arrow (Fig. 5) for the operation upon the supported shoe, the roll 132, pressing against the cam-projection, forces the bar away from the recess, so that it slips under the cam in its yield, without affecting the member 44. When, however, the jack is restored to its initial position by reverse rotation, the bar 134 is in contact with the inner surface of the recess, and is held against oscillation. Consequently, the cam 130 acts to turn the member 44 about its pivot 50, so separating this from the associated member 42 that the toggle 98 is

straightened to lock the jack in its work-receiving position.

To effect the automatic movement of the jack, some such mechanisms as are shown or described in the application previously mentioned, or perhaps better in application Serial No. 312,366, Topham and Morrill, filed July 21, 1919, may be employed. Here it will only be stated briefly that the jack-arm 124 is pivoted at 140 for vertical movement upon a carrier 142 (Fig. 2). This is, in turn, pivoted at 144 in a second carrier 146 to swing transversely of the machine, while the carrier 146 is pivoted at 148 to move from front to rear of the machine. A spring 150 between a rearward extension of the arm 124 and the carrier 142 exerts its force to hold the jacked shoe up into engagement with the stitching mechanism. To feed the work past this mechanism for the operation upon it, a cam 152 of suitable contour (Figs. 1 and 3), fixed upon a driving shaft 154 journaled vertically in the base-casing 14, acts through connections 156 to the member 42 of the jack 25 to impart to the work movement transversely of the front of the machine, swinging the jack upon its mounting on the frame 122. At the same time, the curvature in the periphery of the shoe is allowed for by rotating 30 the jack through connections 158 between another cam on the shaft 154 and the wheel 118. These two component movements permit a sole of any peripheral contour to be presented to the stitching mechanism. To compensate 35 for departures of the sole from a plane surface because of its longitudinal and transverse curvatures, other cams, through connections 160 and 162, respectively tip the jack transversely of the machine upon the pivots 40 144, or from front to rear thereof on the pivot 148. All this is in no respect different from the structures of the previously-mentioned applications; but in the present instance it is not desired, during the return movement of 45 the jack to its initial position after the operation upon the shoe, to carry it outward from the operating mechanism, but merely to raise it sufficiently to free it from the horn. Consequently, the actuating member 164 (Fig. 50 2), which, in the Topham and Morrill machines engages a hook upon a link 166 connected to the jack to thrust it out, in the present organization acts upon the hook to raise the link, and through it the jack. Simultaneously, in the present apparatus, a surface 168 of the member 164 contacts with a rod 170 arranged to slide vertically in the top of the casing 14 and normally lowered by a spring 172. This rod is connected by a 55 link 174 to the arm 40 of the mechanism for controlling the presser-foot. As a result of this, when the jack is lifted by the action of the member 164 upon the link 166, the contact of the surface 168 with the rod so moves the 60 arm 40 that the presser-foot is raised from

the operating position to free the work, and there held until the beginning of the succeeding operation.

In machines of the character of that herein described, it has been customary for the operator to turn the horn manually about a vertical axis to most effectively present its work-engaging extremity to avoid interference with the upper of the shoe and to lessen resistance to movement of the insole over it. In the present apparatus, this rotation of the horn is accomplished automatically, there being secured to the base of the horn, within its bearing (Figs. 2 and 3), a sprocket-wheel 176 connected by a chain 178 to a sprocket 180 fast upon a vertical shaft 182 journaled in the casing 14. Fixed to this shaft 182 is a pinion 184 meshing with a gear-segment 186 upon a lever 188 fulcrumed in the casing and movable horizontally. This lever is joined by a link 190 to a lever 192, also fulcrumed within the casing and having a roll engaging a cam 194 upon a shaft 154. The form of this cam is such as to impart to the horn, through the chain of connecting elements, its rotation during the operation upon the shoe and reverse rotation in the desired timing, the total angular movement in each direction being substantially 360 degrees.

In carrying out my improved method, the upper 312 of the shoe 304 which is to have its outsole attached is fastened over the insole 314 in any convenient manner. The outsole 302, in which are formed the locating openings 300, is laid upon the shoe-bottom, positioned in symmetrical relation to the edge of the insole and its surrounding upper material, and is then temporarily secured in place. This preliminary attachment may conveniently be effected by a staple-tacking machine, the nozzle of which is indicated at 200 in Figs. 7, 8 and 9 of the drawings, the machine being actuated to drive one or more staples through the channel or other portion of the outsole into the insole. Such machines are well known, and will not here be described. To position the outsole with relation to the insole for this operation, gaging mechanism is shown associated with the tacking machine. This may include a presser-foot 202 forked to engage the surface of the outsole at each side of the insole and being situated above a rest 208, which may be raised and lowered by treadle mechanism, which is not illustrated. The presser-foot is guided upon a vertical spindle 204 fixed in a support 206 carried upon the frame of the tacking machine. Mounted in the lower end of the spindle is a pin 210 of such diameter that it will fit snugly one of the locating openings 300 in the outsole, and also a corresponding opening 316 in the insole, it being movable in a bore in the spindle and forced yieldingly down between the arms of the presser-foot by a spring 212 situated within a recess in the spindle. Pivot-

ed upon the support 206, at opposite sides of the spindle, are pairs of levers 214, 214 and 216, 216 the converging upper ends of which are drawn by springs 218 against oppositely inclined surfaces of cams 220 and 222. These cams are movable vertically upon the spindle 204, the cam 220 being yieldably mounted upon the top of the presser-foot by springs 224, while the cam 222 is similarly supported upon its companion by a spring 226. Between the upper cam and the support 206 is interposed a spring 228. The levers are of such lengths that when the upper over the edge of the insole is engaged by the inturned lower ends of the pair 214, 214, the corresponding portions of the pair 216, 216 are in contact with the edge of the outsole. A gage member 230, extending substantially parallel to the nozzle 200 at the opposite side from the presser-foot and with its lower end engaging the shoe-upper, determines the distance of the edge of the sole from the nozzle. In attaching the heel-portion of a sole, the last 320 within the shoe is placed upon the rest 208 with the counter-portion of the shoe against the gage 230, and the rest raised by its treadle to force the work between the pairs of arms 214 and 216. The outsole contacts with the presser-foot, which is lifted by the movement, at the same time raising the cams 220 and 222 and causing their inclined faces to swing the levers of the pairs 214 and 216 toward each other at the same rate. Their contact with the upper and the outsole respectively, moves these laterally until they are symmetrically located. At this time, the openings 300 and 316 in the outsole and insole respectively may be brought into alignment with the pin 210, which will enter the openings, more positively determining the relation between the shoe-elements. The springs 224 and 226, by their yield, permit independent action of the cams 220 and 224 to adapt the mechanism to operate properly upon uppers and associated soles of different widths. The spring 228 allows for continued upward travel of the work after engagement of the levers has been effected. When the outsole, in its movement after the gaging action, comes in contact with the nozzle 200, this trips the locking mechanism, and the attachment of the outsole to the shoe-bottom at this point in its true relation is effected. At the toe of the shoe, the operation is similar to that just described, save here there are no locating openings for the pin 210 to enter, and this pin is permitted by the spring 212 to yield, the levers producing all the positioning action.

The sole being thus temporarily held by the staples in the exact position in which it is to be finally secured, the last is removed, and the operator places the templet upon it, locating the two in the correct relation by the entrance of the templet-pins 60 into the openings 300, and introduces the projection

54 into the socket 52 of the jack (Fig. 4), the shoe passing beneath the sewing mechanism, from which the jack has been lowered at the end of the previous operation, and the upper extremity of the horn entering the opening in the upper. As the shank contacts with the curved end of the lever 74, the locking mechanism, which holds the jack in the work-receiving position, is tripped, and the pressure-lever 80 is brought into contact with the toe-end of the outsole to urge it toward the templet by its pressure against the opposite face. As this is occurring, the member 64 is being raised by the lever 74 against the under face of the sole at the heel of the shoe. Consequently, the work is held between the templet as an upper clamping member of the jack, and the elements 80 and 64 as lower clamping members at both extremities, so that it is grasped positively for the action upon it. The operator may now depress the jack to bring the work into co-operation with the horn, this unlocking the member 164, which assumes its normal position. After turning the jack to bring the starting point for the stitching opposite the operating mechanism, the machine is started by the depression of a treadle, this also lowering the presser-foot against the sole. The templet-flange 62, contacting with the side of the presser-foot at 58, furnishes a fulcrum, so that, under the guidance of the templet, the jack is moved by the cam mechanism along a predetermined path to present the work to the operating mechanism for the insertion of the fastening stitches. This automatic action continues until the opposite side of the shoe is reached, McKay stitching ordinarily being applied from near the breast-line at one side of the shoe to the corresponding point at the opposite side. At this latter point, the jack is lowered by the controlling mechanism, the presser-foot raised, and reverse rotation of the jack takes place to restore it to its initial position. During this time, the action of the cam 130 separates the members 44 and 42 of the jack to release the shoe and lock the parts in position to receive the succeeding piece of work.

The apparatus herein disclosed for use in practicing the method constituting the present invention forms the subject-matter of a divisional application filed December 9, 1927, Serial No. 238,849.

Having described my invention, what I claim as new and desire to secure by Letters Patent of the United States is:

1. The method in shoemaking of operating upon a shoe off the last, which consists in grasping the shoe by the sole, and moving the shoe thus held while performing upon it the desired making operation, the grasp upon the sole being maintained continuously at the same place on the sole throughout such operation.

2. The method of securing the outsoles of McKay shoes, which consists in temporarily attaching an outsole to an insole associated with an upper, holding these elements by the outsole, and stitching the outsole to the insole. 5
3. The method of securing the outsoles of shoes, which consists in applying an outsole to an insole associated with an upper, gaging the position of said outsole with relation to the adjacent portion of the upper, temporarily attaching the outsole to the insole, holding these elements by grasping the outsole, and inserting a series of fastenings through the outsole thus held into the attached elements. 10
4. The method of operating upon shoe-soles, which consists in applying an outsole to an insole associated with an upper, locating a templet upon the outer surface of the outsole by its engagement with openings formed in the sole, and operating upon the outsole under the guidance of the templet. 20
5. The method of securing outsoles to McKay shoes, which consists in temporarily attaching an outsole to an insole associated with an upper, applying a templet to the outsole, and stitching through the outsole and insole under the guidance of the templet. 25
6. The method of operating upon shoes, which consists in applying a positioning member to a shoe-sole, holding the shoe by engagement with its sole only, and operating upon the thus-held shoe under the influence of the positioning member. 30
7. The method of operating upon shoes, which consists in applying a templet to the outsole of a shoe, holding the shoe between the templet and the opposite face of the outsole, presenting the shoe thus held to an operating means, and guiding the shoe while the operation is being performed thereon by said templet. 40
8. The method of securing the outsoles of shoes, which consists in forming locating means upon an outsole, attaching such outsole to an insole having an associated upper, positioning a templet upon the outsole in accordance with the locating means, and inserting fastenings through the outsole and insole under the guidance of the templet. 50
9. The method of securing the outsoles of McKay shoes, which consists in forming an opening in an outsole, applying such outsole to an insole associated with an upper, gaging the position of the outsole upon the insole, temporarily attaching the thus-positioned outsole to the insole, locating a templet upon the outsole by means of the opening therein, and stitching through the outsole and insole under the guidance of the templet. 55
10. The method of securing the outsoles of McKay shoes, which consists in forming an opening in an outsole, applying such outsole to an insole associated with an upper, gag- 60
- ing the position of the outsole upon the insole, temporarily attaching the thus-positioned outsole to the insole, locating a templet upon the outsole by means of the opening therein, holding the shoe by grasping the outsole, and stitching through the outsole and insole under the guidance of the templet. 70
11. The method of operating upon shoes, which comprises utilizing positioning surfaces on a templet to locate the templet in predetermined position on an outsole, which has been associated with the insole and upper of a shoe, clamping the templet and shoe against relative movement and thereafter performing an operation along the margin of the sole under the guidance of the templet. 75
12. The method of operating upon shoes which comprises locating a templet on an outsole, which has been associated with the insole and upper of a shoe, by interengaging positioning surfaces formed at predetermined points on the sole and templet, clamping the templet and shoe against relative movement and thereafter performing an operation along the margin of the sole under the guidance of the templet. 80
13. The method of operating upon shoes which comprises providing positioning surfaces at predetermined points on a templet and on an outsole, locating the templet on the outsole while associated with the upper and insole of a shoe by bringing said positioning surfaces into engagement, clamping the templet and shoe against relative movement and thereafter performing an operation along the margin of the sole under the guidance of the templet. 85
14. The method of operating upon shoes which consists in forming locating means upon an outsole, attaching such outsole to an insole having an associated upper, positioning a templet upon the outsole in accordance with the locating means, and thereafter performing an operation on the sole under the guidance of the templet. 90
15. The method of operating upon shoes, which consists in holding a shoe by engaging at opposite points the upper and lower faces of the shoe-bottom outside of the upper, moving the shoe, and maintaining said hold thereon while performing the desired shoe making operation. 110
- In testimony whereof I have signed my name to this specification. 115
